VOICE MUFFLER

Harry C. Tuttle, New York, N. Y.

Application July 21, 1950, Serial No. 175,102

3 Claims. (Cl. 181—34)

1

The present invention relates to a voice muffler, and more particularly to a voice muffler for a telephone transmitter.

It is an object of the present invention to provide a voice muffler which effectively operates over a range of frequencies which contribute most to the intelligibility of speech transmission by telephone, namely, those frequencies lying between 500 and 2000 cycles per second.

It is a further object of the present invention to provide a filter of the low frequencies between the mouth of the speaker and the outside atmosphere through a construction designed to attenuate these low frequencies by the time they reach the outside atmosphere so that their audibility and intelligibility shall be negligible and in order that these low frequencies, by being allowed to escape in attenuated form, shall not have a blasting effect on the transmitter.

It is a still further object of the present invention to minimize the air blast caused by speech in an enclosed space so that this air blast shall have a negligible effect on the telephone transmitter.

It is still another object of the present invention to make possible a voice muffler as small as possible in cubic content so that the size and weight shall be most practical and convenient for use on the hand-set phone. The design of the present invention above referred to as respects filtering low frequencies and minimizing the air blast is essential to this end.

Another object of this invention is to accomplish the muffling of the voice while at the same time preserving the naturalness and identifying quality of the speaker's voice.

The present invention comprises in its broadest aspects a casing, a highly sound-absorbent entrance wall arranged at one end of the casing and having an entrance aperture, means for attaching the casing to a telephone transmitter with the entrance wall at least partly in the path of at least part of the sound waves to be transmitted by the telephone transmitter, a sound duct arranged in the casing and leading from a location near the entrance wall to the rear end of the casing, and a sound-absorbent material arranged in the casing so as to fill part of the same and to surround a portion of the duct.

In a preferred embodiment of the present invention a wire mesh is arranged at the outer side of the casing and covers at least part of the entrance wall and the aperture.

Preferably an opening is arranged in the rear portion of said casing and the duct leads to a location near the opening.

2

In a preferred embodiment of the present invention the duct subdivides the interior of the casing into a lower part and an upper part containing the entrance wall.

In a preferred embodiment of the present invention the sound-absorbent material includes a first portion and a second portion, the first portion being arranged in the lower part of the casing and filling the same except a lower portion in the rear end of the casing, the second portion being arranged in the upper part of the casing and filling the same except an upper portion in the rear end of the casing and preferably a portion arranged between the duct and the entrance wall, the first portion and the second portion of the sound-absorbent material merging into each other so as to surround the middle portion of the duct.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional elevation of a voice muffler according to the present invention; and

Figs. 2, 3 and 4 are cross-sections taken, respectively, along the lines 2—2, 3—3 and 4—4 of Fig. 1.

Referring now to the drawings, the voice muffler comprises a casing 10 having at one end thereof an entrance wall 12 consisting of a highly sound-absorbent material such as cotton, wool, glass wool, fiber glass or the like. The entrance wall 12 is provided with an entrance aperture 14 arranged approximately at the center of the entrance wall 12. A wire mesh 16 is arranged at the outer side of the casing 10 and covers at least part of the entrance wall 12 and the entrance aperture 14, so as to support the material of the entrance wall. The front part 18 of the casing carries an extension 20 which is provided with an aperture in a vertical side wall 22 thereof for attaching the telephone transmitter 24 to the casing 10. Furthermore, the extension 20 is provided with an aperture 26 the edges of which are curved so as to form a member 28 fitting the mouth of a person using the muffler. The extension 20 forms a chamber of substantially triangular cross-section as shown in Fig. 1.

It will be understood that the entrance wall 12 is at least partly in the path of at least part of

the sound waves to be transmitted by the telephone transmitter.

A sound duct 30 is arranged in the interior of the casing 10 so as to subdivide the same into a lower part 32 and an upper part 34 containing the entrance wall 12. The duct 30 leads from a location near the entrance wall 12 to the rear end 36 of the casing which is subdivided by the duct 30 into a lower portion 38 and an upper portion 40. The upper portion 40 is provided with an opening 42 forming a connection of the interior of the casing 10 with the atmosphere.

The duct 30 is preferably constituted by a lower wire mesh 44 and an upper wire mesh 46 which extend substantially through the entire width of the casing 10 and are connected at the mid portion of the sides thereof by narrow pieces 48 and 50 (Fig. 2) of felt or the like.

A sound-absorbent material such as cotton, wool, glass wool, fiber glass or the like is arranged in the casing 10 and includes a first portion 52 and a second portion 54. The lower portion 52 is arranged in the lower part 32 of the casing 10 and fills the same entirely except the lower portion 38 in the rear end of the casing 10. The second portion 54 is arranged in the upper part 34 of the casing 10 and fills the same except the upper portion 40 in the rear end of the casing 10 and a portion 56 arranged between the duct 30 and the entrance wall 12. The portion 56 has a tapering cross-section having its greatest width at the front portion 18 of the casing 10. The first portion 52 and the second portion 54 of the sound-absorbent material merge into each other as shown in Fig. 2 in the middle portion of the duct 30 so as to surround the same.

The operation of this device is as follows:

The casing 10 is attached to a telephone transmitter as indicated in Fig. 1 and the person who wishes to use the telephone speaks into the opening 26. The sound waves coming from the mouth of the person using the device hit partly the highly sound-absorbent entrance wall 12 of the casing and part of the sound waves enter through the entrance opening 14 and reach the portion 58 of a chamber 56 inside the casing 10, from where they enter the duct 30 leading to the rear portion 36 of the casing 10. The sound waves entering the duct 30 are attenuated by the sound-absorbent material 52, 54, and are then discharged into a chamber arranged in the rear portion 36 of the casing 10 which is in communication with the atmosphere through the opening 42.

Only a small portion of the sound entering through the opening 26 reaches the atmosphere so that any persons being in the same room with the person using the device will not be disturbed by his voice and in order that privacy of conversation may be secured. However, the highly sound-absorbent entrance wall 12 prevents a distortion of the voice so that a person at the other end of the telephone line can clearly recognize and understand the voice of the person using the device.

It will be understood that each of the elements described above, or two or more together, may also find a useful application in other types of voice mufflers differing from the types described above.

While I have illustrated and described the invention as embodied in a voice muffler for a telephone transmitter, I do not intend to be limited to the details shown, since various modifications and structural changes may be made without de-

parting in any way from the spirit of my invention.

Without further analysis, the foregoing will so fully reveal the gist of my invention that others 5 can by applying current knowledge readily adapt it for various applications without omitting features that, from the standpoint of prior art, fairly constitute essential characteristics of the generic or specific aspects of this invention, and, therefore, such adaptations should and are intended 10 to be comprehended within the meaning and range of equivalence of the following claims.

What I claim as new and desire to secure by Letters Patent is:

15. 1. A voice muffler for a telephone transmitter, comprising in combination, a casing; a highly sound-absorbent and sound-permeable entrance layer of free fibrous material arranged at one end of said casing and having an entrance aperture; a wire mesh arranged at the outer side of said casing and covering at least part of said entrance layer and said aperture; means for attaching said casing to a telephone transmitter with said entrance layer at least partly in the path of 20 at least part of the sound waves to be transmitted by the telephone transmitter; a sound duct arranged in said casing and leading from a location near said entrance layer to the rear end of said casing; a sound-absorbent material arranged in said casing so as to fill part of the same and to surround the middle portion of said duct; and a chamber arranged in the rear end of said casing, said chamber forming an empty space surrounding said duct and having an opening 25 connecting said empty space to the atmosphere whereby sound waves transmitted through said duct enter said empty space from which they are discharged in attenuated form through said opening into the atmosphere.
30. 2. A voice muffler for a telephone transmitter, comprising in combination, a casing; a highly sound-absorbent and sound-permeable entrance layer of free fibrous material arranged at one end of said casing and having an entrance aperture; means for attaching said casing to a telephone transmitter with said entrance layer at least partly in the path of at least part of the sound waves to be transmitted by the telephone transmitter; an opening arranged in the rear portion of said casing; a sound duct arranged in said casing and leading from a location near said entrance layer to a location near said opening arranged in the rear portion of said casing; a sound-absorbent material arranged in said casing 35 so as to fill part of the same and to surround the middle portion of said duct; and a chamber arranged in the rear end of said casing and forming an empty space surrounding said duct, said empty space being connected by said opening to the atmosphere whereby sound waves transmitted through said duct enter said empty space from which they are discharged in attenuated form through said opening into the atmosphere.
40. 3. A voice muffler for a telephone transmitter, comprising in combination, a casing; a highly sound-absorbent and sound-permeable entrance layer of free fibrous material arranged at one end of said casing and having an entrance aperture; means for attaching said casing to a telephone transmitter with said entrance layer at least partly in the path of at least part of the sound waves to be transmitted by the telephone transmitter; an opening arranged in the rear portion of said casing; a sound duct arranged in said casing and leading from a location near said entrance layer to a location near said opening arranged in the rear portion of said casing; a sound-absorbent material arranged in said casing 45 so as to fill part of the same and to surround the middle portion of said duct; and a chamber arranged in the rear end of said casing and forming an empty space surrounding said duct, said empty space being connected by said opening to the atmosphere whereby sound waves transmitted through said duct enter said empty space from which they are discharged in attenuated form through said opening into the atmosphere.
50. 4. A voice muffler for a telephone transmitter, comprising in combination, a casing; a highly sound-absorbent and sound-permeable entrance layer of free fibrous material arranged at one end of said casing and having an entrance aperture; a wire mesh arranged at the outer side of said casing and covering at least part of said entrance layer and said aperture; means for attaching said casing to a telephone transmitter with said entrance layer at least partly in the path of at least part of the sound waves to be transmitted by the telephone transmitter; an opening arranged in the rear portion of said casing; a sound duct arranged in said casing and leading from a location near said entrance layer to a location near said opening arranged in the rear portion of said casing; a sound-absorbent material arranged in said casing 55 so as to fill part of the same and to surround the middle portion of said duct; and a chamber arranged in the rear end of said casing and forming an empty space surrounding said duct, said empty space being connected by said opening to the atmosphere whereby sound waves transmitted through said duct enter said empty space from which they are discharged in attenuated form through said opening into the atmosphere.
60. 5. A voice muffler for a telephone transmitter, comprising in combination, a casing; a highly sound-absorbent and sound-permeable entrance layer of free fibrous material arranged at one end of said casing and having an entrance aperture; a wire mesh arranged at the outer side of said casing and covering at least part of said entrance layer and said aperture; means for attaching said casing to a telephone transmitter with said entrance layer at least partly in the path of at least part of the sound waves to be transmitted by the telephone transmitter; an 65
70. 6. A voice muffler for a telephone transmitter, comprising in combination, a casing; a highly sound-absorbent and sound-permeable entrance layer of free fibrous material arranged at one end of said casing and having an entrance aperture; a wire mesh arranged at the outer side of said casing and covering at least part of said entrance layer and said aperture; means for attaching said casing to a telephone transmitter with said entrance layer at least partly in the path of at least part of the sound waves to be transmitted by the telephone transmitter; an 75

opening arranged in the rear portion of said casing; a sound duct arranged in said casing so as to subdivide the interior of the same into a lower part and an upper part containing said entrance layer, said duct leading from a location near said entrance layer to the rear end of said casing; and a sound-absorbent material including a first portion and a second portion, said first portion being arranged in said lower part of said casing and filling the same except a lower portion in the rear end of said casing, said second portion being arranged in said upper part of said casing and filling the same except an upper portion in the rear end of said casing containing said opening, said first portion and said second portion of said sound-absorbent material merging into each other so as to surround the middle portion of said duct, said lower and upper

portions forming a chamber free of sound-absorbent material and having an opening communicating with the atmosphere, whereby sound waves transmitted through said duct enter said chamber from which they are discharged in attenuated form through said opening into the atmosphere.
